Ed. M. Alexander

UNITED STATES PATENT OFFICE.

WILLIAM L. HAAS, OF CHARLES CITY, IOWA.

GATE.

SPECIFICATION forming part of Letters Patent No. 407,951, dated July 30, 1889.

Application filed March 19, 1889. Serial No. 303,922. (No model.)

To all whom it may concern:

Be it known that I, WILLIAM L. HAAS, a citizen of the United States, residing at Charles City, in the county of Floyd and State of Iowa, have invented certain new and useful Improvements in Gates, of which the following is a specification, reference being had therein to the accompanying drawings, in which—

- 10 Figure 1 represents a side elevation of my improved gate in a lowered position; Fig. 2, a view of the elevating devices, the gate being removed to better show them and they being in an elevated position. Fig. 3 is a detail, partly in section, of a portion of the elevating mechanism; Fig. 4, a horizontal section of the rear battens, showing my improved eyebolt; and Fig. 5, a detail view of one of the serrated or roughened pintles.
- 20 The invention has essentially for its object the production of an extremely simple, durable, and practical arrangement for positively and readily adjusting a swinging gate in a vertical direction either for the purpose 25 of compensating for sagging or of elevating it to avoid accumulations of snow, &c., or for any other purpose, as will more fully hereinafter appear.

The invention consists in certain novel 30 features of construction and arrangement, that will be fully hereinafter described, and particularly pointed out in the claims appended.

Referring to the accompanying drawings by letters, A A' represent, respectively, the 35 supporting and latch posts, and B the gate proper, which is constructed, essentially, in this instance of the end battens C C, the center beam D, and the wires E, although it may be constructed in any other suitable manner 40 and be provided with any suitable latch.

F F represent crank-arms or supports journalized in the supporting-post, the horizontal screw-threaded portions of these arms passing entirely through the said post, and 45 provided with thumb-nuts G G, which serve to hold the arms in any desired position, washers G' G' being interposed between these nuts and the face of the post A, as shown in Fig. 1. The horizontal portions of these 50 arms are provided with shoulders a a, which abut against the face of the post when the thumb-nuts G are tightened, and serve to

hold the arms steady and prevent undue vibration of the same. The swinging portions b b of the arms F are provided at their ends 55 with horizontal eyes or journals c, through which pass the horizontal bolts d, which clamp the tubular portions e' of the pintles e firmly to the outer ends of the said horizontal eyes c. The adjacent faces of the parts c and e' 60 are provided with radial serrations to prevent the parts turning when once adjusted, as shown in Fig. 5.

The horizontal bolts d have clamped upon them by means of nuts f f on their ends independent spacing-sleeves g g, these sleeves surrounding the portions of the bolts between the inner ends of the eyes c and the aforesaid nuts f f, washers f' f' being interposed between the latter and the spacing-sleeves. 70

Connecting the two spacing-sleeves g g upon the bolts is a vertical bar I, this bar being provided with holes near its ends for the free passage of the sleeves. By means of the spacing-sleeves it will be observed that 75 the nuts on the ends of the bolts may be tightened to any degree without in the least binding the connecting-bar, which must work loose and free. By means of this connecting-bar the crank-arms will be caused to move in 80 perfect unison when the gate is adjusted either up or down.

The gate is hung upon the vertical pintles e e by means of eyebolts J J, clamped adjustably between the inner battens of the 85 gate by means of nuts h h, tapped on their ends, washers h' h' being interposed between the nuts and battens, as shown. These eyebolts are each constructed with a tapering body portion k, which is adapted to fit 90 between the battens and brace the same. They are also provided with oppositely-projecting shoulders k' k', which abut against the edges of the battens when the nuts are tightened and serve to clamp the same firmly. The 95 body portions k of the eyebolts are formed with slots to render them light and strong.

When it is desired to adjust the gate, the nuts G' and f are loosened sufficiently and the arms F F rotated the proper distance in 100 their bearings in the post A, the pintle-sleeves e' being also rotated so as to keep the pintles e in an upright position, as clearly shown by dotted lines in Fig. 2. When the

gate has been adjusted to the desired elevation, the nuts G' and f are again tightened, holding all the parts in their adjusted position.

5 Having thus fully described my invention, what I claim is—

1. The combination, with a supporting-post, of two crank-arms journaled in the said post and clamped adjustably thereto, pintles secured adjustably to these arms, and a gate supported upon the pintles.

2. The combination of a post, crank-arms supported thereby and carrying eyes at their ends, pintles bolted to these eyes, the adjacent faces of the pintles and eyes being ser-

rated to prevent turning, and a gate hung upon the said pintles.

3. The combination of a post, crank-arms supported by the said post and provided with eyes c , pintles, bolts for securing the pintles to the eyes c , spacing-sleeves on these bolts, nuts for clamping the spacing-sleeves, and a connecting-bar.

In testimony whereof I affix my signature in presence of two witnesses.

WILLIAM L. HAAS.
